UNITED STATES PATENT OFFICE.

FRANK E. GRISWOLD, OF GENEVA, OHIO.

SPECULUM.

No. 872,343.

Specification of Letters Patent.

Patented Dec. 3, 1907.

Application filed March 11, 1907. Serial No. 361,759.

To all whom it may concern:

Be it known that I, FRANK E. GRISWOLD, citizen of the United States, residing at Geneva, in the county of Ashtabula and State of Ohio, have invented certain new and useful Improvements in Speculums, of which the following is a specification.

This invention relates to speculums, and has for its object to provide means whereby 10 the orifices or organs of the human body may be readily examined by the practitioner, or by the patient herself.

The device comprises, speaking generally, a speculum provided with illuminating means such as an electric lamp, and a telescope or sight tube arranged at an angle to the speculum proper, and having at the joint or connection a mirror inclined at a proper angle to reflect, through the tube, the 20 image of the parts disclosed by the speculum. The sighting tube or telescope is extended at a convenient angle to permit of the same being used either by the attendant or by the patient.

25 The invention is illustrated in the accompanying drawings, in which

Figure 1 is a side elevation of the instrument. Fig. 2 is a central vertical section thereof. Fig. 3 is a side elevation of the 30 speculum proper detached and adapted for use alone. Fig. 4 is a sectional view of the parts shown in Fig. 3.

Referring specifically to the drawings, 22 indicates the lower or fixed jaw of an ordinary speculum, and 10 the upper jaw hinged at 13 thereto. The jaws have rearwardly extending rods 40 and 41, the former of which acts as a lever handle to allow the upper jaw of the speculum to be opened or 40 closed. A screw 42 is pivotally attached to the lower rod, and works through a hole in the upper rod and is provided with a nut which may be run down the screw to hold the speculum in open position when desired.

45 The speculum bills so described project from one branch of an angular tubular angle piece or elbow 6 which has at the bottom a mirror 23 held by a removable cap 9. The other branch of the angle piece receives the lower 50 end of a sectional telescopic sight tube 20 which is provided with an eye piece 21. The sections telescope one within the other to enable the tube to be made longer or shorter as desired. The mirror 23 is placed at the 55 proper angle to reflect, through the tube, the

light and image received through the speculum.

The lower jaw of the speculum has at the point thereof a cavity 8, covered by a lens 19 and arranged to receive the small electric 60 lamp 25 which is supplied through a wire 12 which extends through the hollow of the lower jaw and through an opening 15 in the angle piece to attachment with a binding post 14. Another binding post, 14^a, connects the lower jaw with the other side of the circuit.

The current is supplied from a dry battery 50, through the cords 51, and the necessary switches are provided to open or close the 70 circuit. A convenient way of closing the circuit is afforded by means of a conducting cord 52 connected to one pole of the battery and provided at the end with a metal ring 53 which is in the circuit, and which may be 75 worn upon the finger of the operator. When the metal ring is touched to a metallic part of the instrument, the circuit is established and the lamp lighted.

To enable the instrument to be packed in 80 small compass the sight tube 20 has a slip joint with the angle piece 6, and may be readily put on or off. Or, if desired, the speculum may be used without the sight tube, the eye being applied directly to the angle piece, 85 but the sight tube is especially provided to enable a person to use the device and make a personal inspection without the presence or services of another person.

The connection between the angle piece 6 90 and the speculum proper is made by attaching the fixed jaw 22 of the speculum to the angle piece by means of the bolt 14^a, which serves its purpose as well as that of a binding post, as described. By removing the bolt 95 and detaching the parts the speculum is capable of independent use, in which event it will conveniently be turned over, as indicated in Figs. 3 and 4, to bring the jaw having the electric light at the top, so that 100 should any matter run down or leak out it will not interfere with the light.

The advantages of having an instrument capable of modifications in the ways shown is obvious.

I claim:

1. An instrument comprising a tubular angle piece having a reflector at the angle, a pair of speculum jaws one of which is fixed to one branch of the angle piece and the other 110

- 2
of which is hinged thereto, and a sight tube on the other branch of the angle piece.
2. An instrument comprising a pair of speculum jaws and a sight tube, connected by a tubular angle piece provided with a reflector at the angle.
3. An instrument comprising a tubular angle piece having a reflector at the angle, a pair of speculum jaws projecting from one branch of the angle piece and having operating handles projecting rearwardly beside the angle piece, and a sight tube projecting from the other branch of the angle piece.
4. The combination with a speculum having an electric lamp therein in circuit with the metallic part of the speculum, and a battery connected thereto, of a circuit closer

comprising a ring connected to the battery and adapted to be worn on the finger and to close the lamp circuit when brought to contact with said metallic part. 20

5. An instrument comprising a tubular angle piece having a reflector, and a pair of speculum jaws hinged together, one of the jaws being detachably fixed to the angle piece, and said jaws having rearwardly-extending operating handles. 25

In testimony whereof I do affix my signature, in presence of two witnesses.

FRANK E. GRISWOLD.
